RICHARD FOREGGER, OF ROSLYN, NEW YORK

INHALATION APPARATUS FOR ANÆSTHETIC AND OTHER PURPOSES

Application filed June 16, 1927. Serial No. 199,224.

My invention relates to apparatus for administering gas or gases for anæsthetic and other analogous purposes.

The object of my invention is to improve such apparatus, particularly in connection with the meters or devices that show the rate of flow of the gases. More especially, I so arrange the apparatus as to permit an ether bottle or other obstruction to be inserted in the path of the gas at any time without affecting the accuracy of the flow meter or meters; also I so arrange the apparatus as to permit gas flows in excess of the capacities of the flow meters when necessary, and any gases that may pass certain types of meters inadvertently and heretofore wasted to the atmosphere, are now sent on to the patient; and in connection with such apparatus I have provided a scale which permits the same meter, without any adjustment, to be used for substantially any gas suitable for the case in hand although the different available gases have widely different flow characteristics.

The accompanying drawings illustrate an anæsthetic apparatus embodying my invention. Figure 1 is a diagrammatic elevation of the gas machine, with certain representative attachments added thereto. Figure 2 is a sectional elevation of the cap portion of the flow meters shown in Figure 1. Figure 3 is an elevation of one of these flow meters, without the cap, drawn to a larger scale. Figure 4 illustrates a scale for such flow meters suitable for use with gases of different flow characteristics. Figure 5 is a slightly modified form of cap for the type of flow meter illustrated in Figure 1.

In Figure 1, the base or table 1 of the apparatus (which may be provided with a leg 2 or supports to elevate it if desired) is provided with yokes 3 of ordinary form for holding cylinders of the desired gases such as 4. A machine can be arranged for as many cylinders and gases as may be desired; the machine shown in Fig. 1 is arranged for four different gases. The usual shut off valves in the necks of the cylinders are shown, in one instance, at 5. Each yoke 3 is perforated with a horizontal passage to

receive gas from the outlet in the side of the neck of the respective cylinder when the valves 5 are open, from whence the gas passes by the pipes 6, one for each gas, to the flow meter or meters 8. In these passages 6 are interposed, ordinarily, individual control mechanism to reduce the pressure of the gases from that within the cylinders 4 to a pressure only slightly above atmosphere, and to control the rate of flow; ordinarily the valves 5 are opened wide when the machine is in use, the gas flow being controlled by these control devices of the machine. Preferably I use for these control devices those valves 7 which are described and claimed in my Patent No. 1,433,104, dated October 24, 1922, but it will be apparent that my invention is not limited to the use of such valves. At or from the meter or meters 8 the different gases join and flow through a single passage 10 toward the patient. As is well known, ether bottles, when used, are preferably or necessarily inserted in the common passage 10. Illustrative of such attachments which somewhat obstruct the flow of the gas or gases when in use and permit a freer flow of the gases when taken out of service, I have shown an ether bottle at 11. As usual this ether bottle is provided with a valve 11, by means of which the gas or gases can be passed directly through the cap of the bottle or can be made to pass down through the tube 12 and, bubbling out at the bottom of the tube, pass upward through the ether and thence on to the patient. At 13 is indicated a so-called "sight feed" that is frequently used in apparatus of this type, in order that the anæsthesist may observe visually that the gas or mixed gases are actually flowing to the patient. The device illustrated for this apparatus comprises a glass bottle partly filled with water and provided with a tube 14 perforated longitudinally. The gas coming from the common passageway 10 passes down this tube and bubbles out of one or more of the perforations, depending on the quantity being supplied to the patient. From above the water level the gases pass directly to the gas bag 100.

15 ordinarily used, and from thence to the face mask 16. Because of the relatively small volume of gas handled per minute and the necessity of 5 making the machine as small and simple as possible, it is preferable to measure the rate of gas flow (usually the rate of flow of each gas individually), by means of a device or devices directly responsive to gas pressure. 10 Since however attachments such as the ether bottle 11 which offer some obstruction to the gas flow, are usually used only more or less temporarily and occasionally, they afford a variable obstruction, changing the back pressure 15 on the gases as the attachments are put into and taken out of service, and this renders such flow meters inaccurate from time to time. I avoid this and maintain the accuracy of the flow meters by connecting the 20 opposite sides of each pressure instrument to two points along the gas passageway both in advance of the obstructions (ether bottle 11), so that the pressure instrument or instruments responds to the difference between 25 the pressures at these two points in the passageway. This causes the instrument or instruments to give an indication accurately proportional to the rate of gas flow regardless of the presence or absence of obstructions 30 to the gas flow farther along. Preferably the passageway of the gas (or mixture of gases) to be measured is locally restricted, and the pressure instrument is connected to the two sides of the restriction; small 35 changes in the gas flow then cause easily noticeable changes in the reading of the instrument. Each gas or mixture of gases to be measured is provided with such a restriction and pressure responsive mechanism, but 40 where a number of gases are to be measured, certain of the passageways may be common to all, and the meters may be more or less combined in the general manner described with reference to the device illustrated. 45 Thus in the machine of Fig. 1, which, as before stated, is arranged for handling four different gases, for convenience the flow meters are combined into two devices 8, each indicating the rate of flow of two gases. 50 These meters 8 are in the form I regard as preferable. Each of these flow meters shown comprises a transparent (glass) container 21 for liquid (usually water) as more clearly illustrated in Fig. 3, and a pierced block in 55 the form of a special cap indicated at 22 and in Fig. 2. Each cap is pierced with an inlet passage 24 for each individual gas (see Fig. 2) to which a gas passage 6 leads. Each of these inlet passages opens freely to the interior of the container 21 as through the passages 25. At 26 an annular mixing space is provided having an outlet at 23 going to the common passage 10 leading toward the patient; at 9 the gases from the two meters 60 join. Passages 27 and 28 connecting the

inlet passages 24 and the outlet 26—23 provide respectively the localized restrictions. The outlet passage 26—23 leading on toward the patient, is also connected by an ample passage or passages 29 with the interior of the container 21, near the top thereof. Connected to the branches 25 leading off from the respective inlet passages 24, are individual transparent (glass) tubes 32 and 33 extending downwardly into the liquid within the container 21 as indicated in Fig. 3, and open at their bottoms. The normal liquid level (no pressure in the tubes 32 and 33) is at the point marked "Water" on the scale. 70 75

It will now be seen that the gases from the individual cylinders 4, subject to individual control by the valves 7 or other devices for the purpose, are forced to traverse the respective localized restrictions 27, 28 on their way to the patient, and that the pressure of each gas at one side of its respective restriction, for example, the restriction 27, is transmitted by the passage 25 to the interior of the respective glass tube, i. e. the tube 32, while the pressure at the opposite side of the restrictions, in this case the pressure within the mixing space and outlet 26—23, is impressed on the larger surface of the liquid within the container 21, but outside the tubes. Accordingly the surface of the liquid within each tube is depressed below the surface of the liquid outside the tube, a distance proportional to the pressure required to force the respective gas through the respective localized restriction 90 95 100 105 110 115 120 125 130

27 or 28. It will be observed therefore that the device will indicate the quantity of each gas flowing per unit of time, and since the indication depends entirely on the conditions existing at the localized restrictions, the indication is independent of any obstructions to flow that may exist between the flow meter and the patient, for example at the ether bottle 11. It will be observed that the localized restrictions 27 and 28 may be of different diameters or different lengths, or both, depending on the flow characteristics of the respective gases and the quantities respectively required. Of certain gases the quantities required may be measured in cubic centimeters per minute, while a number of liters per minute will be required of other gases. Furthermore the rate of flow of any certain gas through any certain restriction under a given pressure, depends on its molecular weight or specific gravity; thus a certain pressure will pass much less nitrous oxide through a certain hole or restriction than ethylene, and less oxygen than ethylene, but more oxygen than nitrous oxide. The rate of flow or quantity per unit time is dependent upon the molecular weight, i. e. specific gravity, as these examples indicate.

I may use with the container 21 and tubes 130

32 and 33, a scale or scales of the kind indicated in Fig. 3, that is to say, a scale individual to each tube and calibrated for a single particular gas; such a scale will be accurate for the single gas for which it was calibrated and other gases of the same molecular weight. Furthermore the scale for one tube may be calibrated in cubic centimeters per minute and the other in liters per minute, as indicated. By comparing the position of the surfaces of the liquids in the respective tubes with respect to these scales, one may observe the flow rate of the respective gases going on to the patient. As an alternative for the scales of Fig. 3, I may use a scale of the type illustrated in Fig. 4, which adapts a single restriction and pressure responsive device (e. g. tube 32) for use with gases of different molecular weights. Certain commonly used gases are marked at the top of the scale, and the scale can be marked with vertical lines 36 below each gas or group of gases of substantially the same molecular weight. Joining those points on these vertical lines which represent the flow of equal volumes in equal times of the respective gases, are marked lines 37, 38, 39, etc. each representing the flow of a certain quantity of gas per unit of time. Thus the line indicated by the reference character 38 indicates a flow rate of three liters per minute; when the gas is oxygen, the depression of the liquid surface within the tube to the point where line 38 crosses the middle vertical line, indicates that three liters of that gas per minute are flowing; when the gas is nitrous oxide, the surface of the liquid must be depressed to the point where line 38 reaches the right hand vertical line to assure a flow rate of three liters per minute. In rectangular scales, such as are suitable for straight vertical liquid columns such as shown in Fig. 3, these equal-flow-rate lines 37, 38, 39, etc. are generally sloped from one side of the scale to the other. By interpolation, such a scale as illustrated in Fig. 4 can be used not only for the particular gases marked on the scale, but for other gases as well, provided only that the molecular weight or specific gravity of the desired gas is known as well as the molecular weight or specific gravity of the gases marked on the scale. Thus a gas, the molecular weight of which is midway between the molecular weight of nitrogen and the molecular weight of oxygen, if employed with the scale Fig. 4, has its flow rate measured by points on the cross lines 37, 38, 39, etc. midway between the vertical lines 36 respectively directly under the oxygen and nitrogen markings.

In Figure 5, I have illustrated a slightly different form of cap for the flow meter. The inlet passage is at 42 and the outlet at 44. As before, the inlet 42 leads to the tube 32 intended to be suspended within a container

such as 21. The restriction appears at 43 in a passageway leading from the inlet 42 directly into the container, near the top of the latter. The flow of gas from 42 to 44 takes place therefore through the top of the container, differing in this respect from the cap of Fig. 2. The outlet 44 opens from the top of the container as before. Although only one tube 32 appears in the drawing of Fig. 5, it will be apparent that a plurality of tubes may be used with a cap perforated in the manner indicated in that figure.

With my invention as thus applied to flow meters of the liquid type shown, it will be observed also that should any gas be furnished inadvertently to the meters 8 at a greater pressure than can be sustained by the liquid in the tubes 32 or 33, the excess will escape from the bottom of the tube, bubble up through the liquid, and pass to the patient, instead of being wasted to the atmosphere as heretofore with meters of this liquid type on analogous apparatus. Furthermore, this arrangement permits gas to be furnished to the patient in quantities beyond the capacities of the meter or meters under the control of the controller at 7. In some instances it may be desirable to furnish considerable excesses more quickly than the controllers at 7 can be operated, or excesses furnished temporarily without disturbing the setting of the controllers 7. For this purpose I provide another or other by-passes 46. These have respective quick-opening shut-off valves 47 which take their gases from a point between the controllers 7 and the cylinders 4, and they deliver the gas or gases to the patient side of the restriction or restrictions. By opening any valve 47, an excess of the respective gas can be sent on to the patient momentarily both quickly and without requiring that the setting of the controller 7 be disturbed. In order that the surface of the liquid within the tubes 32, 33, and the like may be found quickly by the eye, a float 45 can be placed in each tube; that is to say, a body light enough to float at the surface of the liquid and then follow this surface up and down. Furthermore, the "sight feed" at 13 may constitute a flow meter for the mixed gases; by making the highest perforation in 14 suitable for passing, say, one liter of the mixed gases per minute and each other hole suitable for passing another liter of the mixture per minute, at least the approximate total flow rate can be observed by noting the number of holes through which the gases emerge from the tube 14; thus active emergence of gas from three holes simultaneously indicates that the flow rate of the mixed gases is three liters per minute. I anticipate that knowledge of both the flow rates of the gases individually and the flow rate of the mixture of the gases may be useful in cer-

tain instances. As will thus be observed, my apparatus can afford such knowledge.

While I have illustrated and described certain embodiments of my invention, in detail, it will be understood that my invention is not limited to these details except as appears in the following claims.

Claims:

1. Apparatus of the kind described comprising means for holding a cylinder of gas, a liquid container, a cap for the container pierced with a gas passage connected to the gas cylinder and opening into the container, an outlet passage opening from said container, and a passage providing a restricted passageway through which gas flows from the first mentioned passage on its way to the outlet passage, a sight tube within the container connected to said first mentioned passage and having an opening near its bottom, and means for fastening to said outlet passage an attachment through which the gas may flow on its way to the patient.

2. Apparatus of the kind described comprising means for holding a plurality of cylinders of gas and individual means for controlling the flows therefrom, a liquid container, a cap for said container pierced with passages for conducting the gases unmixed to the container, sight tubes within the container, open near their bottoms, and respectively receiving gas from said passages and a common outlet means for conducting the gases toward the patient, said cap being pierced with individual restricted passages through which the gases flow on their way from the first mentioned passages to said outlet means and said outlet means being connected to said container to receive gas from above the liquid therein.

3. Apparatus of the kind described comprising a liquid container, cap means therefore pierced with a plurality of inlet passages opening into the container, a gas mixing space and outlet, a passage connecting the top portion of the container to the mixing space, and a restricted passage connecting each inlet passage to said mixing space, a sight tube connected to the opening from each inlet passage into the container, said sight tubes extending downwardly into the container and having openings near their bottoms, means for holding a plurality of gas cylinders, and means for connecting the gas cylinders to the respective inlet passages of said cap means including means for regulating the flows of gas therethrough.

4. Apparatus of the kind described comprising means for holding a cylinder of gas, a liquid container, means providing a gas passage connected to the gas cylinder and opening into the container, an outlet passage opening from said container, and a passage providing a restricted passageway for gas from the first mentioned passage to the out-

let passage, a sight tube within the container connected to said first mentioned passage and having an opening near its bottom, a scale adjacent the liquid column within the sight tube, with which the surface of said liquid column can be compared, said scale being marked with lines generally sloping from one side of the scale to the other and indicating substantially equal flow rates of different gases, and means for fastening to said outlet passage an attachment through which the gas may flow on its way to the patient.

In testimony whereof, I have signed this specification.

RICHARD FOREGGER.
